UNITED STATES PATENT OFFICE.

ALEXANDER BOYNTON, OF SAN ANTONIO, TEXAS.

DEVICE FOR TIGHTENING FLEXIBLE LINES.

Application filed March 26, 1925. Serial No. 18,644.

To all whom it may concern:

Be it known that I, ALEXANDER BOYNTON, a citizen of the United States, and a resident of San Antonio, in the county of Bexar and State of Texas, have invented certain new and useful Improvements in a Device for Tightening Flexible Lines, of which the following is a specification.

This invention relates in general to a device for tightening or tensioning flexible lines and is particularly designed and adapted for use in tightening the guy wires used on oil well derricks, gin poles, telegraph poles, telephone poles or the like as well as in tightening small cables, clothes lines, wire fences or the like.

The object of the invention is the provision of a device of this character which may be easily applied to the line to be tightened and easily operated to tighten the line and which is securely held in line tightening position.

One of the principal objects of the invention resides in the provision of a device having the advantages and capacities mentioned which may be applied to either side of the line to be tightened and turned in either direction to tighten the same, the device being so constructed that it will effectively tighten the same in tightened position.

A further object resides in the provision of a line tightener operating in the manner hereinabove set forth and which may be powerfully actuated to set up a high degree of tension in heavy cables.

A still further object resides in the provision of a line tightener of the character specified which is of simple and durable construction, reliable and effective in operation and easy and comparatively inexpensive to manufacture. Other objects and advantages reside in certain novel features of the construction, arrangement and combination of parts which will be hereinafter pointed out in the appended claims, reference being had to the accompanying drawing forming a part of this specification, and in which:

Figure 1 is a view in side elevation showing one embodiment of the invention;

Figure 2 is a view thereof in top plan;

Figure 3 is a view in top plan of another embodiment of the invention;

Figure 4 is a view in side elevation of the embodiment illustrated in Figure 3 but showing the wrench removed;

Figure 5 is a view in section on line 5—5 of Figure 3;

Figure 6 is a view showing a further modified form of the device illustrated in Figure 4;

Figure 7 is a view in elevation illustrating an extension or wrench applied to the handle of the device shown in Figures 1 and 2,

Figure 8 is a sectional view of the device shown in Figure 7,

Figure 9 is a view in side elevation of another embodiment of the invention,

Figure 10 is a sectional view on the line 10—10 of Figure 9, and

Figure 11 is a view in side elevation looking at the opposite side of the device from that shown in Figure 3.

Referring to the drawings and more especially to Figures 1 and 2, numeral 1 designates a hub having a transverse slot 2 extending from a point adjacent its center out through one end thereof. The slot 2 is designed to receive a line designated at L and in the operation this line L is twisted around the periphery of the hub 1. At its ends the hub 1 is formed with retaining fingers 3 which serve to confine the line L on the hub 1. All of the retaining fingers 3 except one taper toward their outer ends and the one retaining finger that does not taper has integrally formed therewith an elongated operating handle 4. The operating handle 4 is aligned with the finger 3 on which it is formed and so is located at one side of the device. Adjacent to but spaced from the outer end of the handle 4 are a pair of oppositely disposed holding hooks 5 which extend inwardly, that is, in the direction of the hub 1.

With this arrangement when a line is to be tightened the device is so positioned that the line extends through the slot 2. The device is then rotated or turned as far as may be necessary to take slack in the line and properly tension the same. Rotation of the hub 1 causes the line L to wind on the hub and this rotation of the hub may be easily effected by the handle member 4. Irrespective of which way the device is turned it may be securely held with the line properly tensioned by engaging the proper hook 5 with the line L. The provision of oppositely disposed hooks makes it possible to hold the line tensioned irrespective of how the device is turned or irrespective of how it is

- applied to the line. In other words, the device may be applied to either side of the line and turned in either direction and yet held in position to maintain the line tensioned. The provision of only a single handle member and the location of both hooks on the handle member facilitates the turning of the hub without interference from the hooks.
- Under ordinary conditions ample power may be easily applied by means of the handle 4 but if a high tension is to be applied to a heavy cable the device shown in Figure 7 may be employed. This consists of an auxiliary wrench or handle extension designated at 6 which may consist simply of a piece of pipe one end of which is adapted to fit over the outer end of the handle 4 and the other end of which is bent as at 7 to provide a gripping portion. The end of the wrench or extension 6 which is fitted on the handle 4 abuts the hooks 5 which also have the function of limiting the inward movement of the handle extension 6 onto the handle 4.
- In the embodiment shown in Figures 3, 4 and 5 a hub designated at 10 is provided and is identical to the hub 1, the hub 10 having a slot 11 and also having retaining fingers 12 integrally formed therewith. The retaining fingers 12 are similar to the retaining fingers 3 of the embodiment hereinabove described but all of these retaining fingers 12 taper toward their outer ends and all of them are provided with openings 13 at their outer ends. The openings 13 are transversely aligned and provide sockets for a pin 14 which is engageable with the line L' to hold the device in line tightening or tensioning position. As will be understood from the inspection of Figures 3 and 4 there is no handle integrally formed with any of the retaining fingers 12 of this embodiment of the invention, but a web 15 is integrally formed with two of the fingers 12 and with the hub 10. The hub 10 is provided adjacent the web with notches 16. A wrench or operating member designated generally at 17 is provided for turning the hub 10 and this wrench 17 may consist of a piece of pipe having its ends bent as at 18 to provide handles. A block 19 is welded to the pipe 17 intermediate its ends and the block 19 is slotted as at 20. The web 15 is received in the slot 19 and both the web and the block are provided with registering openings through which a retaining pin 21 is inserted and suitably secured. The block 19 is formed with reduced extensions or tongues 22 which fit into the notches 16. The purpose of the block 19, web 15 and pin 21 as well as of the notches 16 and tongues 22 is to provide a releasable connection between the wrench or handle 17 and the hub or spool 10.
- When the device shown in Figures 3, 4 and 5 is to be used to tighten a line the line is positioned in the slot 11 and the pin 14 is removed. The wrench 17 is connected with the hub 1 by means of the block 19, web 15 and pin 21 and the handles 18 are grasped and the wrench 17 then turned to wind the wire on the hub 10. When the desired degree of tension has been set up in the wire the pin 14 is introduced through the aligned openings of two of the retaining fingers 12 to hold the hub 10 and retaining fingers 12 in such position as to secure the wire properly tensioned.
- As shown in Figure 6 in addition to the openings 13 in the fingers 12 notches 25 may be formed in these fingers to provide seats or sockets for the pins 14. The pins 14 are held in the notches 25 by the tension of the line L'. Also the web 15 may be omitted and the hub may be formed with a squared socket 26 designed to receive a correspondingly formed projection 27 provided on a wrench 28 which is similar to the wrench 17.
- In the embodiment in Figures 9, 10 and 11 the device includes a hub, indicated at 30, and a pair of retaining elements integral with the hub, the retaining elements comprising circular discs 31 and 32 having enlarged rims 33 and 34, each of which is provided with a circular series of openings 35. The openings 35 of the discs 31 are transversely aligned. The hub 30 is formed with a slot 36 designed to receive the line to be tightened and the disc 32 has a slot 37 which permits the line to be passed into the slot 36. The disc 31 has integrally formed therewith an outwardly projecting web 38 designed to co-act with a wrench having a socket adapted to receive the web and having a suitable shank and handle. The wrench referred to may be of the type shown in Figure 3. The web 38 has an opening 39 so that it may be fastened by a pin or bolt and nut to the socket of the wrench, the socket of the wrench having openings adapted to be aligned with the opening 39. The wrench is illustrated in dot and dash lines in Figure 10.
- I claim:
1. A device for tightening flexible lines comprising a hub having a transversely extending line-receiving slot opening out through one end of the hub and terminating short of its other end, retaining elements fixed on the hub for preventing the line from slipping endwise off the same, said retaining elements having transversely aligned openings, means for turning the hub to wind the line thereon, and a pin insertible in the transversely aligned openings of the retaining elements and engageable with the line for holding the line tightened.
  2. A device for tightening flexible lines comprising a hub having a transversely extending line-receiving slot opening out

through one end of the hub and terminating short of its other end, retaining elements fixed on the hub for preventing the line from slipping endwise off the same, one of said retaining elements having a slot aligned with the slot of the hub to permit the line to be entered into the slot of the hub, said retaining elements having transversely aligned openings, means for turning the hub to wind the line thereon, and a pin insertable in the transversely aligned openings of the retaining elements and engageable with the line for holding the line tightened.

15 3. A device for tightening flexible lines

comprising a hub having a transversely extending line receiving slot opening out through one end of the hub, circular end plates fixed on the hub and having transversely aligned circular series of openings, 20 one of said hubs having a diametrical slot aligned with the slot of the hub to permit the line to be entered into the same, the other plate having means co-operable with a wrench whereby the device may be turned, 25 and a pin selectively insertable in the transversely aligned openings of the plates and engageable with the line for holding the same in position.

ALEXANDER BOYNTON.
